FUSE

Louis Ludwig, Brooklyn, N. Y.

Application August 1, 1946, Serial No. 687,677

3 Claims. (Cl. 200—130)

1

This invention relates to fuses.

It is an object of the invention to provide a fuse whose rupture is delayed upon the application of a slight overload current but which, when it blows under such an overload, makes a quick and positive break.

It is another object of the invention to provide a fuse of the character described comprising relatively few and simple parts which can be manufactured at a low cost and assembled by comparatively unskilled help.

It is a further object of the invention to provide a fuse of the character described which is rugged and highly reliable in operation.

Other objects of the invention will, in part, be obvious and in part hereinafter pointed out.

The invention accordingly consists in the features of construction, combinations of elements and arrangements of parts which will be exemplified in the construction hereinafter described and of which the scope of application will be indicated in the appended claims.

In the accompanying drawings, in which is shown one of the various possible embodiments of the present invention:

Fig. 1 is a side elevational view of a fuse constructed in accordance with the invention;

Fig. 2 is a top plan view thereof with the cap off;

Fig. 3 is a sectional view taken substantially along the line 3—3 in Fig. 2; and

Fig. 4 is an enlarged sectional view taken substantially along the line 4—4 in Fig. 3.

Referring now in detail to the figures, 10 denotes a fuse embodying my invention and comprising a conventional body 12 of porcelain or like insulating material, said body having an upwardly opening interior recess 13 which houses the active fuse elements. The body includes a flared upper rim 14 on which there is mounted a brass cap 16 whose skirt 18 envelopes the rim and is crimped in as at 20 to hold the cap in place. The crown of the cap is provided with a large central aperture 22 through which the recess can be seen. Said aperture is closed by a disc 24 of transparent material, such for example as mica, which is interposed between the crown and the rim 14 to protect the fuse elements without concealing them. An external integral helical ridge 26 on the body receives a threaded brass ferrule 28 whose lower edge has an inturned integral flange 30 abutting against an annular shoulder 32 near the bottom of the body. Said shoulder encircles a pendant projection 34 which is centrally apertured to ac-

2

commodate a hollow headed rivet 36 functioning as the bottom contact for the fuse plug.

An overly long fusible metal strip 38 extends from the bottom contact to the ferrule 28, being connected by a blob of solder 40 to the inside of the shank of the contact and by a blob of solder 42 to the interior of the ferrule. The strip passes through an opening 44 in the side of the body in order to make contact with the ferrule. If desired, fillets 46, 48 of plaster of Paris or some other suitable mastic may be used to cover the soldered ends of the strip in order to improve the appearance of the plug and arrest the electric arc before it reaches the contacts.

15 A portion 50 of the fusible strip is reduced in cross-section to constitute the fuse link. Said link has a cross-sectional area of predetermined size and shape such that the heat generated therein by a current in excess of a certain amount will fuse the link thereby causing an electric circuit to be interrupted.

As thus far described, the fuse plug is entirely conventional and has only been depicted in detail to afford a better understanding of my invention.

Pursuant to my invention I have provided means to somewhat delay the blowing (fusion) of the link, said means being designed to be of particular use when a slight overload is imposed, that is to say, said means should operate to prevent the link from blowing very shortly after the application of such an overload, thus extending the period of time over which the slight overload can be imposed. However, said means should not prevent the link from fusing immediately upon the application of a heavy overload caused, for instance, by a short circuit.

Furthermore, the fuse plug should, in accordance with my invention, incorporate means for quickly making a wide break between the fused ends of the link and interposing a solid dielectric therebetween when the link does blow, so that, despite the delayed incidence of the break under a slight overload, upon occurrence of the break either no arc will be formed or any arc formed will quickly be quenched.

Moreover, both the foregoing means should be of such construction that they can be included in a standard fuse plug with the addition of but few and simple extra parts in order that the fuse may not become unduly complicated and its price unduly high.

As shown herein, the above means, i. e., the means for delaying the blowing of the link and for preventing or quenching the resultant arc,

comprises an element 52 made from a dielectric material, e. g. soapstone, having a high heat storage capacity and a high coefficient of thermal conductivity. Said element is semi-circular in cross-section and has a deep central groove 54 in its flat bottom surface running parallel to the axis of revolution of the curved upper surface of the element whereby the curved upper surface of said element is symmetrical with respect to the closed end of the groove. A shallow arcuate groove 56 is provided in said curved upper surface, the same forming lateral rails 58, 60. The element 52 is supported by a wire bridge 62 of a resilient material, such for instance as steel or Phosphor bronze, which extends through the slot 54 and has its ends resting upon diametrically opposite portions of an annular inset or shelf 64 formed on the inside of the exterior recess 13 adjacent the upper edge thereof.

The groove 56 is slightly wider than the strip 38 so said strip will be confined between the rails 58, 60 and, as a result, the element 52 will be secured in definite relationship with respect to the strip until the fuse blows. The element 52 is designed to keep the strip under tension by pressure applied at the link 50 and for this purpose the length of the overly long strip 38 is made such that when said element lies under the slack bend of the strip and is urged upwardly by the spring wire 62 it will take up all of the slack while the strip is still bowed under tension, as indicated by the solid lines in Fig. 4. In other words, the normal operating position of the fuse elements seen in Figs. 3 and 4 is such that the fuse strip is kept under tension by upward pressure of the element 52 against the link 50 arising from bowing of the wire 62.

The element and wire are placed in this position by first introducing the wire beneath the slack of the fusible strip and placing the ends of the wire on the shelf 64. At such time, the wire, which has a slight preformed curvature imparted thereto, does not contact the fusible strip. Then the element is set astride the wire on one side of the fusible strip and is pressed downwardly to markedly bow the wire and permit the element to be slid along the wire into position beneath the strip. Now when pressure on the element is released, it will engage the strip at the link 50 and taunt the same.

When a slight current overload is imposed on the plug, the fuse link 50 will have heat generated therein at a rate so rapid that, if it were not for the presence of the element 52, the fuse would very quickly blow. However, the element 52 absorbs this heat almost as fast as it is generated, thereby keeping down the temperature of the fusible strip. Of course, after the passage of some time the element 52 will itself become heated to quite a high temperature and will absorb heat more and more slowly allowing the link to reach its fusion temperature, whereupon the fuse will blow.

It is particularly emphasized that as the element 52 heats and the fusible link expands while the temperature is rising, said element continuously engages the link under the biasing force of the spring wire 62, thus maintaining good contact between the strip and element and insuring excellent heat transfer up to the time that the strip blows.

As soon as the fuse link 50 melts, the dielectric element 52 will be sprung upwardly by the wire 62 to rapidly part the two ends of the strip formerly bridged by the link. Said element thus will be in-

4
troduced between said ends and rapidly quench any arc that may have been formed upon blowing the fuse.

It will thus be seen that I have provided a fuse which achieves the several objects of my invention and is well adapted to meet the conditions of practical use.

As various possible embodiments might be made of the above invention and as various changes might be made in the embodiment above set forth, it is to be understood that all matter herein described or shown in the accompanying drawings is to be interpreted as illustrative and not in a limiting sense.

Having thus described my invention, I claim as new and desire to secure by Letters Patent:

1. A fuse plug comprising a hollow dielectric body, a fusible elongated member housed in said body with its ends fixedly supported at points spaced apart a distance less than the length of said member thereby providing slack in the member, said member including a portion having a cross-sectional area less than that of the remainder of said member, a dielectric element of material, such as soapstone, having a high heat storage capacity and a high coefficient of thermal conductivity, said element being centrally disposed in said body out of contact with the walls thereof and having a curved surface beneath and in surface contact with the portion of said member of lesser cross-sectional area, and an elongated slender resilient normally straight wire having its ends unconfined and resting on shelves at opposite sides of said body adjacent the top thereof, said wire extending across the interior of said body and passing through an opening in said element, said wire being bowed under pressure away from the top of said body so as to resiliently urge said element toward said member whereby the heat generated in said member portion upon the application of a slight current overload will be absorbed by said element so as to delay the fusion of said member.

2. A fuse plug comprising a hollow dielectric body, a fusible elongated member housed in said body with its ends fixedly supported at points spaced apart a distance less than the length of said member thereby providing slack in the member, said member including a portion having a cross-sectional area less than that of the remainder of said member, a dielectric element of material, such as soapstone, having a high heat storage capacity and a high coefficient of thermal conductivity, said element being centrally disposed in said body out of contact with the walls thereof and having a symmetrically curved surface beneath and in surface contact with the portion of said member of lesser cross-sectional area and an elongated slender resilient normally straight wire having its ends unconfined and resting on shelves at opposite sides of said body adjacent the top thereof, said wire extending parallel to the axis of symmetry of the curved surface across the interior of said body and passing through an opening in said element, said wire being bowed under pressure away from the top of said body so as to resiliently urge said element toward said member whereby the heat generated in said member portion upon the application of a slight current overload will be absorbed by said element so as to delay the fusion of said member.

3. A fuse plug comprising a dielectric fuse body having an upwardly opening interior recess, a threaded electrically conductive shell around the

side walls of said body, a central contact at the bottom of said body, a fusible electrically conductive elongated member in said recess, the ends of said member being permanently electrically connected to said bottom contact and said shell, a major portion of the length of said member being curved whereby to provide slack in the member within the recess, a soapstone element having a curved surface engaging the underside of said member, the underside of said element having a downwardly opening recess which extends from side to side of said element, an elongated slender resilient normally straight wire disposed in said recess and on which said element is supported, the ends of said wire being unconfined and resting on shelves on opposite sides of said body adjacent the top thereof, said wire being bowed under pressure away from the top of said body so as to resiliently urge said element against said member, whereby to delay the fusion of said member

upon the application of a slight current overload and to quickly quench the arc that may be formed when the fuse blows.

LOUIS LUDWIG.
